[57] **ABSTRACT**

A quick-connect vent tube used in the filler valves of automatic bottle and can beverage filling machines. Vent tube is of unitary one-piece construction formed from corrosion-resistant metal or thermoplastic material for long term use and high resistance to bacterial accumulation on the vent tubes, and has an O-ring seal connection for mounting in a valve. The seal acts as a sealing arrangement and concurrently retains the tube in the filler valve. In another embodiment, a filler valve, which is of the standard threaded vent tube connector type, has an adaptor fastened thereto to provide for the quick-connect seal connection of a vent tube having no threaded connecting portion thereon.

QUICK-CONNECT VENT TUBE STRUCTURE

This invention relates to vent tubes and, more particularly, to an improved vent tube adapted to be utilized in the filling valve arrangements of high-speed container filling machines.

In the bottling or beverage industry, it is extremely important, from an economic viewpoint, that containers be rapidly and efficiently filled with their intended liquid contents. This pertains to all types of alcoholic and non-alcoholic beverages, carbonated or non-carbonated, intended for use in bottles or metallic containers. In essence, the empty bottles or cans are automatically conveyed in a high-speed sequence to the fluid or liquid product filling unit of the bottle filler (or can filler) machine. High-speed automatic bottle and can fillers are well known in the industry and, consequently are not described in detail with reference to the present invention. The bottle fillers essentially include high-speed filling valves which fill the bottles with the desired liquid product at predetermined filling rates and velocities while concurrently controlling the counterpressure in the bottles, liquid flow and snifting or venting of the bottles back to atmospheric pressure.

When the bottles are filled with liquid product by the high-speed filling valves, pressures in the bottles, cans or containers tend to rise at rapid rates. The bottles must accordingly be vented during filling in order to prevent them from cracking or exploding. In order to accomplish the satisfactory venting of the bottles, the high-speed filling valves incorporate vent tubes extending into the bottles during filling thereof, which are adapted to place the interiors of the bottles in venting communication with the exterior thereof or with the atmosphere.

Essentially, the vent tube of the filling valve comprises an elongated hollow cylindrical tube extending coaxially and concentrically with the valve axis so as to be able to enter the bottle or can opening during filling thereof with a beverage, without actually touching the bottle or valve. The beverage flows about the vent tube into the bottle or can with suitable sealing means being provided between the filling valve and bottle neck to thereby prevent spilling or bubbling out of the beverage as it enters the bottle. The lower tip of the vent tube which is adapted to extend into the bottle during filling, is usually closed by a cap or closure member fastened to the cylindrical tube. One or more holes or slots are provided in the cylindrical portion of the vent tube so as to place the interior of the tube in communication with the interior of the bottle during filling of the latter with a beverage. By placing the hollow vent tube in communication with the atmosphere, gases or air in the bottle or can being displaced by the filling beverage will be able to escape through the vent tube and thereby minimize or eliminate the possibility of bottles or cans exploding during filling due to excessive gas or air pressure accumulations.

Although presently used vent tube construction has, in general, been satisfactory during bottle and can filling operations, it has been subject to several disadvantages and drawbacks, particularly during extensive periods of use in the high-speed filling machines. Thus, there is a tendency for the attached vent tube lower end closures to work loose after periods of time due to the constant pressure fluctuations to which they are subjected during the continuous bottle filling cycles and

sequences. This, of course, presents the hazard and risks of the closure member or cap falling into a bottle being filled, with the possibility of personal injury to a retail purchaser or user of the bottled beverage, and resultant liability of the bottler to the retail purchaser. Furthermore, vent tubes having separate cap or closure members provide the risk of harmful bacteria collecting and cultivating at the juncture between the cylindrical tube portion and the cap. As a consequence, there is an inherent danger that the beverage being filled into the bottles or cans may be contaminated with bacteria destructive to the quality of or detrimental to the taste and texture of the beverage, or even injurious to the person drinking the beverage. Another aspect to be considered is the cost of separately manufacturing the caps and assembling them with the tube portion in order to form the completed vent tube assembly.

These disadvantages have been largely obviated by forming the vent tube cylindrical portion and the lower end or closure into a single-piece or unitary construction. Preferred embodiments of unitary vent tubes possessing the required characteristics discussed hereinabove are disclosed in my copending U.S. application Ser. No. 56,568, filed July 20, 1970, now abandoned.

The vent tubes which are presently utilized in the industry are connected at their upper ends to the filler valves. These connections invariably consist of the upper end cylindrical portion of the vent tubes having an externally threaded portion which is adapted to be threaded into the filler valves, the latter of which include suitable complementary internal threads. A particular drawback of the threaded connections between the vent tubes and the filler valves lies in that it is difficult to manipulate them for engaging or disconnecting movement when it is desired to remove or change vent tubes during operation. The threaded connections frequently tend to jam together or form liquid product residues between the threads. Furthermore, the threading and unthreading requirements cause the machines to be shut down for undue lengths of time, thereby adversely affecting the economic productivity of the entire bottling apparatus.

As disclosed herein, the vent tube construction according to the present invention eliminates the need for threaded connection between the vent tube and its associated filler valve by providing a novel and improved quick-connect configuration on the cooperating portions of the vent tube and filler valve. For this purpose, one embodiment of the present vent tube includes a plurality of annular or peripheral grooves extending about its outer cylindrical surface adjacent the upper end thereof, with sealing ring members being positioned in each of the grooves and having outer diameters larger than the diameter of the vent tube at that portion. Correspondingly, the part of the filler valve receiving this grooved sealing ring-containing segment of the vent tube, includes internal annular grooves adapted to be axially or longitudinally aligned with the outer grooves on the vent tube, thereby causing the outer diameters of the sealing ring members to engage the filler valve grooves. This will position the vent tube and its associated filler valve in an axially locked or engaged position through the engagement of the aligned grooved by the sealing ring members.

In a further embodiment of the invention, the filler valve, which includes an internally threaded orifice for attachment of the vent tube, is provided with an

adapter nipple having an external thread at one end adapted to threadingly engage the threaded orifice of the valve. The other end of the adapter nipple is formed into a tubular extension having at least one external annular groove for receiving a sealing ring member. Correspondingly, the hollow interior of the vent tube is dimensioned to closely and slidably fit over the tubular extension of the adapter nipple. The inner surface of the vent tube, adjacent its upper end, is provided with at least one annular groove which is aligned with the exterior annular groove of the adapter nipple upon assembly therewith, thereby causing the outer diametral portion of the sealing ring member to engage in the space formed by the aligned grooves. This will effectively lock the adapter nipple and the vent tube into predetermined axial engagement. Although the embodiment has been described with reference to a single groove, it is readily apparent that two or more spaced grooves, each receiving a sealing ring member, may be employed in carrying out the present invention.

Another aspect of the grooved connection is that the sealing ring members act as fluid seals while concurrently acting as locking members between the vent tube and filler valve.

Accordingly, it is an object of the present invention to provide an improved and novel vent tube for a container filling machine.

Another object of the present invention is to provide an improved vent tube construction adapted for quick connection to the filler valve of a bottle filling apparatus.

Yet another object of the present invention is to provide an improved vent tube formed of an inert material comprising a quickly attachable component of a high-speed filling valve for an automatic bottle or can beverage filling machine.

A further object of the present invention is to provide a novel vent tube having a grooved sealing ring containing end portion adapted to matingly engage with a cooperatively grooved portion of a filler valve so as to facilitate quick connection thereto while concurrently forming a fluid seal construction.

A still further object of the present invention is to provide a novel vent tube having a grooved inner surface bore at its upper end portion adapted to matingly engage with a sealing ring-supporting member of an adapter to facilitate quick connection to a standard threaded filler valve while concurrently forming a fluid seal construction.

These and other objects and many of the attendant advantages of this invention will be readily appreciated as the same becomes better understood by reference to the following detailed description when considered in connection with the accompanying drawings, in which:

FIG. 1 is an assembly, partially in section, of high-speed beverage filler valve assembly incorporating a vent tube according to the present invention;

FIG. 2 is a sectional view of a vent tube according to the present invention;

FIG. 3 is a partially sectional view of a second embodiment of the vent tube according to the present invention;

FIG. 4 is an enlarged, fragmentary sectional view of the vent tube assembled in a filler valve;

FIG. 5 illustrates an adapter nipple for connecting a filler valve having a threaded orifice to another em-

bodiment of a vent tube according to the present invention;

FIG. 6 is a sectional view of a vent tube used in combination with the adapter nipple of FIG. 5; and

FIG. 7 is a fragmentary sectional view of the adapter nipple and vent tube assembled in a filler valve.

Referring now to the drawings, wherein like reference characters designate like or corresponding parts throughout the several views, FIG. 1 illustrates a high-speed filling valve assembly 10 adapted to be installed in a typical commercial bottle or can beverage filler apparatus. The filling valve 10 and the automatic filler apparatus (not shown) are both widely known in the bottling and beverage canning industry and need not be described in detail in connection with this invention.

As shown in FIG. 1 of the drawings, the filling valve 10 includes a vent tube 12 which forms the subject matter of the invention. During the filling cycle of a continuous sequence of bottles 14 being fed into the beverage 20 filler apparatus, a self-centering sealing gasket 16 forming a part of the filling valve 10 positions itself over the opening or neck 18 of a bottle 14 stationed below the filler valve 10. The vent tube 12 projects into the bottle 14 in spaced relationship with the neck and walls 25 thereof so as to avoid the inadvertent cracking or shattering of the bottle 14.

The desired beverage, alcoholic or non-alcoholic, carbonated or non-carbonated, is fed into the bottle through the filling valve aperture 20 at predetermined 30 feed rate and pressure. Since the sealing gasket 16 forms a generally air and fluid-tight seal about the neck 18 of the bottle 14, avoid excessive pressurizing and consequent explosion of the bottle 14. This venting means is provided by the vent tube 12 extending into the bottle 14 during the filling of the latter with the beverage.

The vent tube 12, as illustrated in the embodiment of FIG. 2 of the drawings, comprises essentially an elongated hollow cylindrical portion 22 extending at one end into a closed hemispherical tip or closure cap 24 which may be formed integrally with the cylindrical portion. The other end 26 of the vent tube includes a pair of axially spaced annular grooves 28 and 30 encompassing the outer periphery of the tube. Although each of the grooves 28 and 30 are illustrated as being of essentially rectangular cross-sectional configuration, other shapes such as V-shape or hemispherical contours may be utilized in forming the grooves. One or more apertures 32 may extend through the wall of cylindrical portion 22 immediately adjacent to closed end 24 so as to place the hollow interior of the vent tube in communication with the exterior thereof adjacent to its closed end or closure cap 24.

During the filling of bottle 14 with a beverage from filling valve 10, air or gases accumulated in the bottle will enter the hollow interior of vent tube 12 through apertures 32, and will be vented to the atmosphere in a suitable manner, as for example, by way of a venting valve (not shown) attached to filler valve 10. The vent tube 12, if desired, may be formed from a single unitary piece of material.

The embodiment of the vent tube 40 in FIG. 3 of the drawings is similar to that of vent tube 12 with the exception that this embodiment includes an annular spreader 42 forming a portion of the periphery of the hollow cylindrical portion 44 of the vent tube. The spreader 42 consists essentially of a frusto-conical an-

nulus extending about cylindrical portion 44 with its enlarged base toward the closed end of the vent tube 40. This, in effect, will mix the beverage as it flows from the filler valve 10 into the bottles 14.

Referring to FIG. 4 of the drawings, the vent tube 12 (or 40) is shown assembled in a filler valve 10. Each of the grooves 28, 30 has positioned therein an annular resilient ring gasket 50, generally known as an O-ring. The O-ring gasket has an outer diameter which, when installed in groove 28 or 30 is larger than the outer diameter of the vent tube. The sleeve portion of the valve 10 which is adapted to receive the vent tube has a cylindrical bore 52 which permits a sliding fit with the vent tube 12 or 40. A pair of spaced grooves 54, 56 are cut internally of the bore 52 and are axially spaced so as to correspond to the spacing of grooves 28, 30.

When the vent tube, having the gaskets 50 located in each of the grooves 28, 30 is telescopingly slid into the filler valve bore 52, the gaskets 50 are compressed into the vent tube grooves. As the grooves 28, 30 and valve grooves 54, 56 come into axial alignment, the gaskets 50 expand radially or circumferentially outwardly to thereby have their outer radial portions extend into grooves 54, 56. This will effectively lock the vent tube 12 or 40 into the filler valve 10. Concurrently, the gaskets 50 also provide a generally fluid-tight seal between the vent tube and the filler valve.

In order to separate the vent tube 12 or 40 from the filler valve 10, it is merely necessary to impart a downward pull on the vent tube, thereby compressing the gaskets 50 and allowing the tube to slide out of valve bore 52.

Referring now to the embodiment illustrated in FIGS. 5 and 6 and 7 of the drawings, the filler valve is of the presently known standard type, having a lower liquid outlet orifice 60 provided in a stem 62 with an internally threaded portion 64. In the prior art constructions, the upper ends of the vent tubes included an external thread adapted to matingly engage with the threaded portion 64.

As shown in FIGS. 5 and 7, in order to eliminate the requirement for providing the vent tube with threads, an adapter nipple 66 is connected to the filler valve stem 62.

The adapter nipple 66 has a longitudinally extending axial bore 68 for permitting flow of liquid product therethrough from the filler valve outlet orifice 60. One end of the adapter nipple 66 is formed into an externally threaded portion 70 which is dimensioned to engage the internally threaded portion 64 of the filler valve stem 62. In order to provide a gripping surface for assembling adapter nipple 66 onto valve stem 62, the intermediate segment of the adapter nipple is shaped into a hexagonal or rectangular nut 72 so as to form a contact or clamping surface for a wrench or spanner.

The other, or lower end portion of the adapter nipple 66 is formed into a smooth-surfaced tubular extension 72 adapted to be inserted into the closely dimensioned bore 74 of a vent tube 76.

As shown, the tubular extension 72 includes a pair of spaced annular grooves 78. The bore 74 of the vent tube 76 includes a pair of similarly spaced internal grooves 80.

The annular grooves 78 are adapted to each receive an annular resilient ring gasket 82, generally known as an O-ring. The gasket 82 has an outer diameter which,

when installed in the groove 78 is larger than the diameter of vent tube bore 74.

When the vent tube 76 is telescopingly slid over the adapter nipple extension 72, the latter of which has a gasket 82 positioned in each groove 78, the outer diameters of the gaskets are resiliently compressed until they correspond to the diameter of the bore 74. As the grooves 78 on the nipple extension 72 and the grooves 80 in the vent tube bore 74 come into axial alignment, the gaskets 82 expand radially outwardly so as to fill the annular spaces formed by the aligned grooves 78 and 80. This will then lock the vent tube 76 into the adapter nipple 66 and filler valve. The gaskets 82 also, concurrently, provide a generally fluid-tight seal between the adapter nipple and the vent tube.

As in the other embodiments, in order to separate the vent tube 76 from the filler valve, it is merely necessary to impart a downward pull on the vent tube, thereby compressing the gaskets 82 and allowing the vent tube 20 to be disengaged from adapter nipple extension 72.

Generally, it is preferable to construct the vent tubes from a corrosion-resistant metal, such as stainless steel or aluminum alloy. However, it has been found that various types of thermoplastic material will also be 25 inert to deterioration during long periods of contact with the beverages and may be readily employed in lieu of metallic vent tubes.

The foregoing disclosure relates to only preferred embodiments of the invention, and is intended to cover all changes and modifications of the example of the invention herein chosen for the purposes of disclosure, which do not constitute departures from the spirit and scope of the invention.

What is claimed is:

1. In an apparatus for the high-speed filling of containers with fluids or the like, the combination of a filling valve device including vent tube means adapted to extend into said containers during filling; said vent tube means comprising;

an elongate hollow cylindrical member, said cylindrical member having one end formed into a closed portion, the other end of said cylindrical member being open and adapted to be attached to means defining a fluid outlet bore of said filling valve, at least one venting aperture extending through the side wall of said cylindrical member adjacent its closed end portion, said venting aperture being in communication with the hollow interior of said cylindrical member so as to provide venting passageway means during the filling of said containers, and the open end portion of said tube means including a plurality of annular grooves in spaced relation, and a sealing ring member in each of said grooves and being dimensioned so as to engage said valve bore means for attaching engagement therewith.

2. An apparatus as defined in claim 1, wherein said cylindrical member includes a plurality of venting apertures extending through its side wall in communication with the hollow interior of said vent tube.

3. An apparatus as defined in claim 1, wherein said grooves are provided on the annular external surface of said tube means, said sealing ring members each having an outer diameter larger than the diameter of said tube means so as to engage said valve bore means.

4. An apparatus as defined in claim 3, wherein said fluid outlet bore means includes a plurality of grooves in axial alignment with the grooves on said vent tube,

said valve bore grooves being adapted to receive the outer diametral portions of said sealing ring members.

5. An apparatus as defined in claim 1, wherein said fluid outlet bore means comprises an adapter nipple for attaching said vent tube to said filling valve device; said adapter nipple having an upper threaded portion for threadingly engaging said filling valve device, a lower cylindrical portion adapted to be slidingly inserted into the open end of said hollow cylindrical member, a plurality of annular grooves in spaced relation being provided on the external surface of said cylindrical portion of the nipple, said grooves on the cylindrical member of said vent tube being interiorly thereof, and said sealing ring members interlocking said adapter nipple and said vent tube upon insertion of the latter into the for- 15

mer.

6. An apparatus as defined in claim 1, wherein said vent tube includes a spreader means formed integrally therewith, said spreader means comprising a generally frusto-conical annular flange encompassing a portion of said cylindrical member, and the base portion of said annular flange being positioned toward the closed end of said vent tube.

7. An apparatus as defined in claim 1, wherein said vent tube consists essentially of a metallic material.

8. An apparatus as defined in claim 7 wherein said metallic material comprises stainless steel.

9. An apparatus as defined in claim 1, wherein said vent tube consists essentially of thermoplastic material.
